UNITED STATES PATENT OFFICE.

DAVID J. POWERS, OF CHICAGO, ILLINOIS.

CRIB OR CHILD'S BED.

SPECIFICATION forming part of Letters Patent No. 394,010, dated December 4, 1883.

Application filed March 22, 1886. Serial No. 196,137. (No model.)

To all whom it may concern:

Be it known that I, DAVID J. POWERS, a citizen of the United States, residing at Chicago, in the county of Cook and State of Illinois, have invented new and useful Improvements in Crib-Beds, of which the following is a specification.

My invention relates to improvements in crib-beds; and it consists in several new devices fully set forth, and described in the accompanying drawings and specification.

The drawings, Figure 1, Sheet 1, show a side view of the crib in its normal condition. Fig. 2 shows an end view, with the reversible rocker turned up, so as to only form a supporting-girt for the legs; and Fig. 3 shows a cross-section of one end on line X X of Fig. 1, with the rocker-girt in position for a rocker. Fig. 4, Sheet 2, shows an end elevation of Fig. 1, 20 with the panels folded down. Fig. 5 shows a modification of the crib in which the frame is not sufficiently raised to allow the panels to fold without first removing the bedding. Fig. 6 shows a longitudinal central section of Fig. 1. Fig. 7 shows the lock for connecting the end and side panels. Fig. 8 shows the plate into which the key locks. Fig. 9 shows a double hinge with which to connect the side panels to the frame, so that the panels can be folded 25 down, out, or inside. Fig. 10 shows the lock upon the reversible rocker adapted to keep it in either position. Fig. 11 shows the locking-key, and Fig. 12 the locking-plate, of the rocker, all of which are indicated by corresponding letters and figures, both in the drawings and specification.

My improved child's crib is preferably constructed with a frame having sufficiently high sides, Fig. 1, A, upon which the folding panels B are hinged to permit the panels to fold down, as shown in Fig. 4, upon the bedding, which in such case would not have to be removed before folding the panels, while with a frame, as shown by Fig. 5, the bedding has 45 to be removed before folding the panel sides and ends. Near the bottoms of these frames is stretched lengthwise and secured a woven wire or other suitable bed-bottom, C. Fig. 6 shows the side and end panels, B and B', which are hinged to the top sides of the frame, so that they can be folded level, the side

panels being folded under preferably. When the panels are erect, they are secured at their intersecting corners by the locking-keys D, which are adapted to be turned in the posts 55 E, and secured from withdrawing by a pin, C', in the groove C'', or by any other suitable means. Key D is fitted with a thumb-piece, d, and locking end d'', flattened so as to pass through the elongated mortise in plate G, 60 Fig. 8. Said plate is secured to the ends of the top rails of the side panels, B, as seen in Fig. 7, in such position and relation to the key in the post that the one enters the other when the panels are brought together, and by 65 a quarter-turn of the key is securely locked in the mortise, and the panels thus firmly connected and disconnected by the reverse action of the parts.

The legs M are adapted to be folded and 70 unfolded in the usual way, and may be secured when unfolded by hooks I, or in any other suitable manner. The legs are connected by a cross-girt, J, at their upper ends and by a curved girt, K, at their lower ends, that is piv- 75 otally secured between the legs, as indicated at k', and adapted to be turned on its axis upward, so that the legs support the crib, or may be turned down, in which position it sustains the weight and serves as a rocker. 80 The rocker-girts are of a length equal to the distance between the inner faces of the legs to which they are secured, and, as the legs are pivoted to the rails of the body in such manner as to fold up inside of such rails, 85 it is apparent that the rockers present no obstruction to the folding of the legs within the body of the crib. This feature is of importance in many ways—as, for example, in the packing and shipping of the cribs, in their 90 storage when not in use, and in the convenience of disposing of the crib during the day, for which purpose it is usually provided with casters secured to the under side of the frame to adapt it to be rolled under an ordinary bed, 95 and with which casters the rockers would interfere did they project beyond the bottom of the rail. Besides, when the rockers are thus pivoted all danger of breaking them by accidental collision is avoided, and the bed is ren- 100 dered more convenient in use as well as improved in appearance.

Fig. 12 shows a plate for securing the rockers in either position, as is seen applied in Fig. 10, together with its locking-latch L.

Fig. 9 shows a double-acting device for hinging the side panels, so that they can be folded either out or in, it often being desirable to fold one of them out and downward when bringing the crib up to the side of a bed, so that it will be out of the way between the bed 10 and crib.

When the panels and legs of the crib are folded, as shown in Fig. 4, and with casters M upon the under side of the crib-frame, it can be readily run under a bed out of the way 15 during the day. Thus altogether my improved child's crib will be found to be very compact, cheap, and convenient in use.

I wish it understood that I contemplate the use of the several features of my invention, 20 set forth in the preceding description and enumerated in the several claims, applied separately and independently of each other to cribs and other articles of furniture, as well as their use together in one article of 25 furniture, as herein shown.

Having thus described my improvement, what I consider as new, and desire to secure by Letters Patent, is as follows:

1. The combination, with posts E, of the end panels having a hole therethrough, of the 30 locking-keys D, passed through said hole and provided with the groove c'' and the locking-head d', the pins c', engaging the groove in the key, and the panels B, provided with the plates G, with which the head d' engages, all arranged and operating as shown and described.

2. The combination, with legs H, of the reversible girt-rockers K, pivoted to and between the legs and of a length less than the distance between the side rails of the crib, a 40 locking-plate secured to the rocker, and a latch secured to the leg and engaging said plate, whereby to secure the girt-rockers in either position, substantially as described.

DAVID J. POWERS.
